TUBE RESHAPING PLIERS WITH INTERNAL AND EXTERNAL WALL ENGAGING MEMBERS

Marvin C. Reynolds, Fostoria, Ohio

Application May 21, 1954, Serial No. 431,343

2 Claims. (Cl. 81—15)

This invention relates to a hand tool and more particularly to a tool of the pliers type.

The primary object of the invention is to facilitate the reshaping of the mutilated end of a length of relatively soft deformable tubing to restore the end of the tubing to its initial circular contour.

Another object is to enable the end of the tubing to be readily restored to its initial diameter and to facilitate the coupling of the length of tubing to a fitting or the like.

The above and other objects may be attained by employing this invention which embodies among its features crossed handles mounted to move toward and away from one another about a common axis, substantially semicircular tube embracing jaws carried by the handles and extending outwardly therefrom for movement by said handles about the common axis adjacent one side of the tool and contraction into engagement with a length of tubing adjacent a mutilated end thereof, and substantially semi-circular anvils carried by the handles and extending outwardly therefrom between the jaws for entrance into the length of tubing embraced by the jaws and expansion into contact with said length of tubing as the jaws contract thereabout.

Other features include a compression coiled spring carried by and extending between the handles for expanding the handles under yielding pressure and holding the jaws expanded and the anvils contracted.

Other features include disposing the concave sides of the arcuate jaws toward one another and disposing the curved sides of the anvils toward the concave sides of opposite jaws.

Still other features include inclining the jaws adjacent the ends thereof remote from the handles to guide the jaws onto a length of tubing, and inclined extensions carried by the anvils and extending longitudinally therefrom for guiding the anvils into the length of tubing.

In the drawing:

Figure 1 is a fragmentary side view of a hand tool embodying the features of this invention, portions of the handles being broken away;

Figure 2 is a view similar to Figure 1, showing the jaws contracted and the anvils expanded;

Figure 3 is a longitudinal sectional view taken substantially on the line 3—3 of Figure 2;

Figure 4 is a transverse sectional view taken substantially on the line 4—4 of Figure 2;

Figure 5 is a transverse sectional view taken substantially on the line 5—5 of Figure 2;

Figure 6 is an exploded fragmentary perspective view of the jaws and anvils; and

Figure 7 is a plan view of one of the jaws.

Referring to the drawings in detail, this tool designated generally 10 comprises crossed handles 12 and 14 connected together by a pivot 16 for movement about a common axis. Carried by the handle 14 and extending longitudinally therefrom is an extension 18 carrying an arcuate jaw 20 and an arm 22 which extends outwardly

2

from the extension 18 adjacent the jaw 20 and carries adjacent its end remote from the extension 18 an anvil 24 having a convex surface 26 on the side thereof remote from the concave surface 28 of the jaw 20.

Carried by the handle member 12 and extending longitudinally therefrom adjacent the extension 18 is an extension 30 carrying an arcuate jaw 32, the concave surface 34 of which is disposed toward the concave surface 28 of the jaw 20 and carried by the extension 30 and projecting outwardly therefrom is an anvil 36, the convex surface 38 of which is disposed toward the concave side of the jaw 20.

The ends of the jaws 20 and 32, respectively, are inwardly inclined as at 38 to aid in guiding the tool into proper position about the end of a length of tubing, and carried by the anvils 24 and 36 are tapered extensions 40 which, assist in guiding the anvils 24 and 36 into the tubing. A compression coiled spring 42 extends between the handles 12 and 14 to yieldingly urge the handles apart and the jaw members into expanded position, as illustrated in Figure 1.

In use, the expanded tool is placed over the end of a piece of tubing to be straightened with the anvils 24 and 36 entering the interior of the tubing while the jaw members 20 and 32 encircle the exterior of the tubing. Upon advancing the handles toward one another, the jaws 20 and 32 will be advanced into contact with the exterior surface of the tubing adjacent the end thereof while the anvils 24 and 36 will be expanded into contact with the tubing so that by repeatedly expanding and contracting the jaw members and rotating the tool about the tubing, the mutilated end thereof may be restored to its initial condition.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

1. A hand tool for reshaping a mutilated end of a length of relatively soft deformable tubing, said tool comprising pivotally connected crossed handles to move toward and away from one another about a common axis, substantially semicircular tube embracing jaws carried by the handles and extending laterally therefrom for movement thereby about the common axis from one side of the tool and contraction into engagement with a length of tubing adjacent a mutilated end thereof, crossed extensions carried by the handles adjacent the jaws, and substantially semicircular anvils carried by the extensions and extending laterally therefrom between the jaws for entrance into the length of tubing embraced by the jaws and expansion into contact with said length of tubing as the jaws contract thereabout.

2. A hand tool for reshaping a mutilated end of a length of relatively soft deformable tubing, said tool comprising pivotally connected crossed handles to move toward and away from one another about a common axis, a substantially semicircular tube embracing jaw carried by one of the handles and extending laterally therefrom for movement by said handles about the common axis from one side of the tool and contraction into engagement with a length of tubing adjacent a mutilated end thereof, a substantially semicircular anvil carried by said one handle and extending laterally therefrom adjacent the concave side of the jaw, an arm carried by the other handle and extending between the jaw and the anvil, a second anvil carried by the arm for movement by the other handle between the jaw and the first mentioned anvil, and a second jaw carried by the other handle in

spaced relation to the second anvil and in opposed relation to the first jaw, the ends of the jaws remote from the handles being inclined inwardly to define guides for guiding the jaws onto a length of tubing, and inclined extensions carried by the anvils and extending longitudinally therefrom for guiding the anvils into the length of tubing.
